UNITED STATES PATENT OFFICE.

MARTIN MOEST AND RUDOLF MÜLLER VON BERNECK, OF HÖCHST-ON-THE-MAIN, GERMANY, ASSIGNORS TO FARBWERKE VORM. MEISTER LUCIUS & BRÜNING, OF HÖCHST-ON-THE-MAIN, GERMANY, A CORPORATION OF GERMANY.

PROCESS OF TREATING NITRIC ACID BY ELECTROLYSIS.

1,040,379.

Specification of Letters Patent.

Patented Oct. 8, 1912.

No Drawing.

Application filed July 26, 1911. Serial No. 640,653.

To all whom it may concern:

Be it known that we, MARTIN MOEST, Ph. D., chemist, and RUDOLF MÜLLER VON BERNECK, chemist, citizens of the Empire of Germany, residing at Höchst-on-the-Main, Germany, have invented certain new and useful Improvements in the Process of Treating Nitric Acid by Electrolysis, of which the following is a specification.

10 In the processes of treating nitric acid by electrolysis in the cathode-compartment of an electrolytic cell without adding other electrolytes, there have hitherto been used only metallic electrodes, generally platinum, 15 in special cases copper, mercury or the like. Now, we have made the observation that these metals can be advantageously replaced in most cases by carbon or graphite electrodes. We have found that carbon or 20 graphite as cathodes are absolutely stable in nitric acid. This observation is most surprising in view of the fact that carbon or graphite when used as anodes in nitric acid are destroyed in a very short time, and must 25 also be regarded otherwise as unstable against the action of nitric acid. (Compare Dammer *Handbuch*, 1894, vol. II, part 1, page 62.) Thus, in the process described in German Patent No. 180052 there may be 30 used a carbon or graphite electrode in the place of the platinum electrode without essentially altering the results. Now, as carbon is much cheaper than platinum, a considerable technical advance is attained by 35 the said invention.

When using platinum electrodes in the electrolysis of diluted nitric acid, for instance of a strength of about 20-30 per cent., in the cathode-compartment there occurs an evolution of hydrogen at the beginning of the electrolysis or on continuing the test, even after a short interruption of the current, and there is always some time required until the normal course of the process 45 is attained, which consists principally in the reduction of nitric acid to ammonia. Similar observations have already been made by

Schönbein (*Poggendorf's Annalen*, 1839, vol. 47, page 563.) This evolution of hydrogen at the platinum cathode, which is 50 caused by its easily becoming passive, is very dangerous for technical purposes, because the gaseous compounds of nitrogen and oxygen which may escape simultaneously, or the access of air in the gas outlets are capable of easily producing an explosive mixture of gases. However by using in the place of platinum cathodes, carbon or graphite cathodes and an anode of platinum or of any other material not dissolving in nitric acid, the diluted nitric acid is chiefly reduced into ammonia, while 55 hydrogen is not evolved. Moreover the required voltage of the current is lower. Furthermore carbon or graphite cathodes show 60 great technical advantages over those made of metals. In the electrolysis of diluted nitric acid with aluminium-cathodes ammonia, for instance, forms, but the aluminium-electrode is thereby sensibly attacked and it requires a very high tension. 65 Carbon or graphite used as cathode, give chemically the same result, namely ammonia with a yield of the current of about 70 60%. However carbon has the advantage over aluminium of being absolutely stable; moreover the required tension and consequently the consumption of energy is much lower. Under otherwise the same conditions the voltage has been for instance: 75 80

With a current density of..... 1.6 5.5 9 amperes.
The density for aluminium as cathode... 2.0 4.2 5.8 volts.
" " carbon ... 1.8 8.4 4.3 "

Copper and mercury, which were occasionally used in laboratory tests as cathodes 85 in the electrolysis of nitric acid, do not, technically, enter into consideration at all, as they are, as is known, unstable against the action of nitric acid and undergo in combination with it reaction while forming 90 nitric oxide gases.

Having now described our invention, what we claim is:

1. The process of electrolyzing nitric acid.

which consists in passing an electric current through an electrolyte of nitric acid to a cathode of carbon.

2. The process of electrolyzing nitric acid, which consists in passing an electric current through an electrolyte of nitric acid to a cathode of graphite.

In testimony whereof, we affix our signatures in presence of two witnesses.

MARTIN MOEST.

RUDOLF MÜLLER VON BERNECK.

Witnesses:

JEAN GRUND,

CARL GRUND.
